UNITED STATES PATENT OFFICE.

GEORGE B. BERGEN, OF CHICAGO, ILLINOIS, ASSIGNOR, BY MESNE ASSIGNMENTS, TO AUTOPPOINT PENCIL COMPANY, OF CHICAGO, ILLINOIS, A CORPORATION OF ILLINOIS.

LEAD-PENCIL.

1,359,568.

Specification of Letters Patent. Patented Nov. 23, 1920.

Application filed March 19, 1918. Serial No. 223,813.

To all whom it may concern:

Be it known that I, GEORGE B. BERGEN, a citizen of the United States, and resident of Chicago, in the county of Cook and State 5 of Illinois, have invented certain new and useful Improvements in Lead-Pencils, of which the following is a specification.

My invention relates to lead pencils and particularly to an improved pencil of simplified design from the standpoint of manufacture.

The objects of this invention may briefly be stated to be the provision of a compact lead propelling mechanism in which use is 15 made of two relatively rotatable parts, one of which travels away from the other, there being means for preventing an excess of torsion such as might cause a bending or breaking of either part. It will further appear 20 that the pencil of this invention may be very cheaply constructed and be operated with certainty under all normal conditions of use, due to its improved and novel features of construction.

25 The invention will be more readily understood by reference to the accompanying drawing, wherein,

Figure 1 is a longitudinal sectional view through a pencil constructed in accordance 30 with my invention;

Fig. 2 is an elevation, partly in section, showing the plunger and filler;

Fig. 3 is an enlarged sectional view on the line 3—3 of Fig. 1;

35 Fig. 4 is a similar view on the line 4—4 of Fig. 1,

Fig. 5 is a similar view on the line 5—5 of Fig. 2, and

Fig. 6 is a sectional view similar to Fig. 40 4, showing, however, a plunger of triangular, instead of flat cross section.

In the drawings it will be seen that the body 10 of the pencil is provided with a longitudinal axial opening 11, of substantially uniform size from end to end thereof. In the pointed end of the pencil I fixedly mount a cylindrical filler 12, which is preferably composed of a relatively soft material such as papier mâché. The extreme 45 point 13, of the pencil is preferably composed of hard rubber or similar material. The papier mâché filler is provided with an axial opening substantially the size of the lead 14, and because of the nature of the 50

material the lead will be frictionally held 55 therein irrespective of slight variations in the diameters of different leads.

At its inner end the filler 12, is provided with a cap or metallic member 15, which is firmly fixed to the filler, the cap being provided with a slot 16, of substantially the size of the flat, threaded plunger 17. The edges of the plunger are threaded, the threads being preferably formed by stamping or pressing. It will be noted that the plunger is 60 uniform from end to end thereof and that the same fits snugly within the slot 16, formed in the end of the cap 15. The plunger is advanced by reason of its engagement with the threads 18, formed in the end of 65 the rotatable sleeve 19, and the end of the sleeve and the cap 15, are substantially in contact. By reason of this arrangement there is no tendency to twist the plunger which is likely to occur where the threaded 70 sleeve and the means for preventing rotation of the plunger are separated to any material extent. The points being in such close proximity the operation is without interference or binding. It will be noted also 75 that the opening 20, in the threaded sleeve is of a diameter substantially equal to the width of the plunger and therefore that the plunger is maintained in perfect alinement in all positions. This is likewise true of 80 the lead opening in the filler, the plunger being alined and maintained substantially in contact at all points in the length of the opening. There is therefore no opportunity 85 for the plunger to wobble or become twisted. 90

The rotatable sleeve is securely fixed at its outer end to a head 21, which as shown in Fig. 3, is provided with notches 22, in its periphery, into which a portion of the collar 23, is pressed to maintain the parts 95 in nonrotatable engagement. The collar is likewise crimped into engagement with the body by means of the rings 24, the collar having the capacity for rotation on the body in a well known manner. A rubber eraser 100 25, may be located in the extension of the collar if desired.

It will be seen that the rotation of the collar 23, will have the effect of reciprocating the flat plunger 17, and that the lead 105 will be advanced as required. The means for holding the lead at points throughout its length assures that it will not be easily

broken. I have found that one of the prolific causes of the breakage of lead is because the lead is not securely held at all points in its length.

5 In the construction of Fig. 6, the body 25, and sleeve 26, remain the same. The plunger 27, however, is of triangular instead of flat cross sectional shape, the corners or angles carrying the threads instead of the edges 10 as in the flat plunger. The operation is the same as heretofore described.

15 Various other modifications may be made in the structure shown and such modifications I consider within the spirit of my invention.

I claim:

20 1. A pencil having a hollow body containing at one end a filler in which is an axial opening to receive therein a lead and plunger for advancing the same, an apertured cap fixedly arranged at one end of the filler and having walls in flush relation with those 25 of the filler, and a plunger having means for effecting propulsion thereof longitudinally of the body and through the cap to expel the lead from the pencil, the plunger being formed to coöperate with the aperture in the cap to travel therethrough without rotation, substantially as described.

30 2. A pencil having a hollow body containing at one end a filler in which is an axial opening to receive therein a lead and plunger for advancing the same, an apertured cap fixedly arranged at one end of the 35 filler having side walls in flush relation with those of the filler, a threaded plunger adapted to travel through the aperture of

the cap and within the filler opening to expel the lead from the pencil, the plunger being formed to coöperate with the aperture 40 in the cap to travel therethrough without rotation, and means for propelling the plunger longitudinally of the pencil comprising a rotatable sleeve having its inner end adjacent the cap and being formed in 45 teriorly at that end with threads which coöperate with the plunger threads whereby the plunger is advanced with rotation of the sleeve, substantially as described.

3. A pencil having a hollow body containing at one end a filler in which is an axial opening to receive therein a lead and plunger for advancing the same, an apertured cap fixedly arranged at one end of the filler, a flat plunger adapted to move longitudinally 55 of the body and through the aperture in the cap and opening in the filler, the edges of the plunger being threaded, and a sleeve rotatably arranged within the pencil having its inner end adjacent the cap and being 60 formed at that end with internal threads adapted to coöperate with the threads on the plunger whereby the plunger is advanced longitudinally of the pencil with rotation of the sleeve, the aperture in the cap being of 65 a size and shape to receive the plunger without permitting its rotation therein, substantially as described.

Signed at Chicago, Illinois, this 14th day of March, 1918.

GEORGE B. BERGEN.

Witness:

T. D. BUTLER.
